United States Patent Office.

PETER HENDRICKS, OF FLORIS, IOWA.

Letters Patent No. 71,483, dated November 26, 1867.

IMPROVEMENT IN BRIDGES.

The Schedule referred to in these Letters Patent and making part of the same.

TO ALL WHOM IT MAY CONCERN:

Be it known that I, PETER HENDRICKS, of Floris, in the county of Davis, and State of Iowa, have invented a Suspension-Bridge; and I do hereby declare the following to be a full, clear, and exact description thereof, reference being had to the accompanying drawings, making part of this specification, in which—

Figure 1 is a side elevation of my improved bridge, showing the two end trestles with portions of the span broken away.

Figure 2 is an elevation of one end of the bridge.

Figure 3 shows a mode of supporting the bridge upon a pier when two or more spans are employed.

Similar letters of reference indicate corresponding parts in the three figures.

This invention relates to an improved mode of constructing suspension-bridges which are composed of a combination of wood and metal, and sustained by means of chains arranged in a catenary, and connected at their ends to strong trestles or towers.

The invention provides for constructing a cheap and very simple suspension-bridge, which shall possess great strength and durability, and which can be constructed by ordinary workmen, as will be hereinafter described.

To enable others skilled in the art to understand my invention, I will describe its construction and operation.

In the accompanying drawings, A A represent the supports at the shore ends of the bridge, which are made up of masonry, so as to form solid, unyielding foundations. B B are the transverse sill-beams, upon which are supported the ends of longitudinal sills B¹ B¹, which incline backward, as shown in fig. 1, and afford supports for the upright timbers or "towers" B² B², which latter are erected perpendicularly upon their sills, and braced by the struts a a. These frames or trestles are securely framed together and anchored down upon their shores A A, so as to afford safe and strong supports for the bridge. Upon the inclined sill-beams B¹ B¹ planks are nailed, so as to form aprons, C, upon which the roadway is constructed of earth and stones, extending up to a level with the flooring or roadway of the bridge for the purpose of loading the trestles or "towers," and preventing their upper ends from approaching each other by the application of weights upon or the passing or repassing of loads over the bridge. The upper ends of the perpendicular standards B² B² are further braced by means of tie-rods b b, extending from said upper ends down to the longitudinal sill-beams B¹ B¹, and secured in a suitable manner thereto. Through the upper ends of the standards B² B², eye-bolts or links c c pass, to the outer ends of which the tie-rods b b are connected, as shown in fig. 1, and to their inner ends the suspension-chains D are connected. These chains consist of rods of suitable length, connected together by means of eyes or links, formed on three ends in a suitable manner. The ends of the rods composing the chains may be connected by binding and linking them together, and using bands, e, so as to form eyes which will not draw out under ordinary strain. At one or more points in each chain, provision may be made, by means of turn-buckles or other devices, for contracting the chains, should they extend too much after the bridge is erected. From these chains D, strips F F are suspended at suitable points, which consist of twisted rods of different lengths, according to the position which they occupy in the curve of the chains, and which have eyes formed through their lower ends for receiving the ends of horizontal transverse floor-beams G G, and firmly holding these beams in their proper places. These beams should all be supported in the same horizontal plane where it is desired to have a horizontal roadway over them. For preventing lateral displacement of the floor-beams, I shall notch their ends, so that the lower ends or loops of the stirrups F F will securely embrace them at the notched points. Upon these floor-beams the stringers J are secured by means of bolts, and when the bridge is of such length of span as to require splicing of the stringers, the ends of the latter are placed side by side on the floor-beams and securely bolted together, and then fastened to each one of the floor-beams at each crossing in a substantial manner. The flooring-timbers K are nailed upon the stringers in the usual manner, and upon this floor the binders or guard-rails L are secured, which latter prevent wagons from running against the sides of the bridge.

In fig. 3 I have represented a mode of supporting two spans of bridge upon a pier, M. It will be seen that the sills and apron shown in fig. 1 are dispensed with, and the frame or trestle N secured upon the said

pier by means of anchors and bolts, the former of which are embedded deeply into the masonry of the pier, and the latter passed through the sills of the trestle, and connected to the anchor-rods.

I am aware that wire suspension-bridges with stone piers or abutments are not new, but I am not aware that a combined of truss and wire suspension-bridge, like what I have shown, has ever been devised.

What I claim, therefore, as new, and desire to secure by Letters Patent, is—

1. The combined wire-suspension-chain or cable and truss-bridge, constructed substantially in the manner herein described and shown.

2. The twisted wire stirrups F, applied substantially in the manner and for the purpose described.

3. The combination of the wooden trusses B² N, braced, stayed, and anchored substantially as shown, with the wire suspension-chain or cable D, wire stirrups F, and the platform K, all substantially as described.

PETER HENDRICKS.
